[57] **CLAIM**

The ornamental design for a wiper blade for a windshield wiper, as shown.

DESCRIPTION

FIG. 1 is an end elevational view of a wiper blade for a windshield wiper showing my new design;

FIG. 2 is a bottom perspective view thereof on a reduced scale;

FIG. 3 is a bottom perspective view thereof on a reduced scale showing the end opposite to that in FIG. 2; and

FIG. 4 is a top plan view thereof on a greatly reduced scale.

Fig. 1

Fig. 2

Fig. 3

Fig. 4
